CLAIM

The ornamental design for a cup apparatus for cue stick, as shown and described.

DESCRIPTION

FIG. 1 is a top perspective view of the cup apparatus for cue stick, showing the new design;

FIG. 2 is a front elevational view of the cup apparatus for cue stick thereof;

FIG. 3 is a top plan view of the cup apparatus for cue stick thereof;

FIG. 4 is a bottom plan view of the cup apparatus for cue stick thereof;

FIG. 5 is a cross-sectional view taken along the line 5-5 in FIG. 1 thereof; and,

FIG. 6 is an environmental view of the cup apparatus for cue stick thereof.

The rear elevational view of the cup apparatus for cue stick is a mirror image of the front elevational view of the cup apparatus for cue stick shown in FIG. 2.

The right side elevational view of the cup apparatus for cue stick is a mirror image of the front elevational view of the cup apparatus for cue stick shown in FIG. 2.

The left side elevational view of the cup apparatus for cue stick is a mirror image of the front elevational view of the cup apparatus for cue stick shown in FIG. 2.

The broken lines in the drawings illustrate environmental subject matter and form no part of the claimed design.
